HAIRPIN COMB

Nathan L. Solomon, Mount Vernon, N. Y.

Application August 29, 1941, Serial No. 408,717

7 Claims. (Cl. 132—20)

The invention is a one piece hair pin comb and the objects and functional and structural advantages thereof will be apparent from the following detailed description taken with the accompanying drawing wherein:

Fig. 1 is an elevational view of the comb according to my invention.

Fig. 2 is a plan view on the line 2—2 of Fig. 1, and

Fig. 3 is a bottom view of Fig. 1.

According to the invention the one piece comb C includes a pair of rows R and R¹ of U-shaped and identical hair pins P¹, P², P³, P⁴ etc. arranged in staggered and overlapping relation as shown, for example, the upper loop or bight portions 10 of the front row of pins R are staggered in respect to the loop or bight portions 11 of the rear row R¹.

Each pin of rear row R¹ comprises a bight portion 11 having a pair of spaced teeth or prongs generally designated 12 each characterizing outwardly bowed or curved upper limbs 13 and the outwardly inclined lower limbs 14.

Similarly each pin of the front row R embodies a loop 10 having spaced prongs or teeth broadly denoted 15 comprising the upper outwardly and arcuately bowed limbs 16 and the outwardly diverged limbs 17.

Thus by the present arrangement, it is apparent that the juxtaposed and overlapping pins form a multiplicity of auxiliary hair pins, for example, the teeth 15 of the spaced pins P², P⁴, and P⁶ of the front row R straddle adjacent teeth 12 of pins P¹, P³, and P⁵ of the rear row R¹, hence forming additional hair clamping means or auxiliary pins defined by teeth 15 and the teeth or legs 12.

In addition the adjacent teeth 15 of the front row of pins P² and P⁴ and P⁶ also form auxiliary hair pins but these are straddled by the teeth 12 of the rear row of pins. Moreover hair clamping pins are also formed by the adjacent teeth 12 of the rear row of pins P¹, P³, and P⁵ and these are interposed between legs 15 of the front row of pins. Hence it is apparent that the gripping action of the comb is materially multiplied as desired.

The throats or gaps T of the auxiliary pins defined by the depending and contiguous legs or teeth 12 and 15 diverge outwardly and cooperate to conveniently receive a desired amount of hair subsequently retained in a clamped relation by upper bowed limbs 13 and 16 of the overlapping pins. In a similar fashion throats T¹ defined by the contiguous legs 12 of adjacent pins P¹,

P³, P⁵, etc. of the rear row are utilized to accommodate a part of the hair subsequently clamped by the contiguous or adjacent upper limbs 13. The adjacent or contiguous teeth 15 of the front row of pins likewise form throats or gaps T² to receive the hair and the upper limbs 16 thereof clamp such hair as is well appreciated.

Portions of the pins P¹ and P² and P⁶ and P⁷ are shown in dotted lines for purposes of illustrating the manner in which the comb may be extended to any suitable length desired but generally speaking the comb need only have the length shown by the full lines of the drawing.

The pin comb herein disclosed is preferably of a plastic material and the lower limbs 14 and 17 thereof of course are in the same plane as illustrated in Fig. 3.

Various changes may be made in details of construction and arrangement of parts without departing from the spirit of the invention or sacrificing any of the advantages thereof inherent therein.

I claim:

1. In a one piece hair pin comb, front and rear rows of hair pins disposed in overlapping relation, the pins of each row comprising a loop having spaced teeth, the loops of said rows being staggeredly arranged for positioning adjacent teeth of contiguous pins of said rear row between said spaced teeth of a pin of said front row.

2. In a one piece hair pin comb, united front and rear rows of hair pins disposed in overlapping relation, the pins of each row comprising a loop having spaced teeth, the loops of said rows being staggeredly arranged for positioning adjacent teeth of contiguous pins of said front row between said spaced teeth of a pin of said rear row.

3. In a one piece hair pin comb, front and rear rows of hair pins disposed in overlapping relation, the pins of each row comprising a loop having spaced teeth, the loops of said rows being staggeredly arranged for positioning adjacent teeth of contiguous pins of said rear row between spaced teeth of a pin of said front row, said adjacent teeth defining an auxiliary hair pin, and said adjacent teeth defining with said spaced teeth spaced auxiliary hair pins.

4. In a one piece hair pin comb, front and rear rows of hair pins disposed in overlapping relation, the pins of each row comprising a loop having spaced teeth, the loops of said rows being staggeredly arranged for positioning adjacent teeth of contiguous pins of said front row between said spaced teeth of a pin of said rear

row, said adjacent teeth defining an auxiliary hair pin, and said adjacent teeth defining with said spaced teeth auxiliary hair pins.

5. A comb having a multiplicity of hair pins formed by a plurality of rows of loop hair pins disposed alternately and in staggered relation in respect to one another.

6. A comb comprising a plurality of united hair pins, one of said hair pins having spaced depending outer legs including outwardly bowed upper portions and downwardly and outwardly extending lower portions, another hair pin of said plurality having depending inwardly arranged legs disposed between said first mentioned legs and comprising inwardly bowed upper portions interposed between said first mentioned upper bowed portions and having spaced lower portions interposed between said downwardly and outwardly extending lower portions, one of said outer legs and one of said inwardly disposed legs constituting hair pin means each having

upper outwardly bowed portions and lower diverging portions.

7. A one piece comb comprising a plurality of merged hair pins, one of said hair pins having spaced depending outer legs including outwardly bowed upper portions and downwardly and outwardly extending lower portions, another hair pin of said plurality having spaced depending inwardly arranged legs interposed between said outer legs and comprising closely spaced inwardly bowed upper portions interposed between said first mentioned upper bowed portions and having spaced lower portions interposed between said downwardly and outwardly extending lower portions and spaced therefrom, one of said outer legs and one of said inwardly disposed legs constituting hair pin means each having upper outwardly bowed portions and lower diverging portions.
